UNITED STATES PATENT OFFICE.

WILLIAM A. KEMP, OF SAN FRANCISCO, CALIFORNIA.

DESIGN FOR A PARLOR-ARCH.

SPECIFICATION forming part of Design No. 23,453, dated July 10, 1894.

Application filed December 22, 1893. Serial No. 494,499. Term of patent 3½ years.

To all whom it may concern:

Be it known that I, WILLIAM A. KEMP, a citizen of the United States, residing in the city and county of San Francisco and State of California, have invented a new and original Design for Parlor-Arches; and I do hereby declare the following to be a full, clear, and exact description of said invention, such as will enable others skilled in the art to which it

10 most nearly appertains to make, use, and practice the same.

My design for a parlor arch is composed of a horizontal beam, *a*, with keystone, *b*, at its middle, triangular supporting brackets, *c*, under each end, short columns, *d*, below the brackets, and square pedestals, *e*, upon which the columns, *d*, rest, and which extend down to the floor. The horizontal beam, *a*, of the arch has an ornamental molding, *f*. The

corner brackets, *c*, are parallel, and each panel 20 has a convoluted vine with a bird perched upon the vine. The columns, *d*, have each a backing, *h*, behind it, and this backing has a rectangular portion, *j*, extending across above the column, and between it and the bracket. 25 Each column has scroll work at its upper end. The square pedestal, *e*, is made with panels on its three exposed sides.

What I claim, and desire to secure by Letters Patent, is—

30 The design for a parlor arch, as herein shown and described.

In testimony whereof I have hereunto signed my name.

WILLIAM A. KEMP.
